UNITED STATES PATENT OFFICE

1,927,555

PROCESS OF CONCENTRATING LIQUIDS

Friedrich August Oetken, Frankfort-on-the-Main, Germany, assignor to American Lurgi Corporation, New York, N. Y., a corporation of New York

Application December 12, 1930, Serial No. 501,935,
and in Germany December 23, 1929

4 Claims. (Cl. 159—47)

This invention relates to a process of concentrating liquids.

The economical operation of concentration apparatus is often greatly impaired through the effect of incrustations on the heating surfaces, resulting in a reduction of the capacity and increased consumption of heat. For this reason, ways and means have long been sought for preventing incrustation on the heating surfaces and thereby improving the efficiency of concentration processes.

The partial improvements heretofore effected, however, were still far from constituting a complete solution of the problem, and therefore were in no wise satisfactory. The efficiency of the means employed has been insufficient and more or less a matter of chance.

The most troublesome of all incrustants are the lime salts (especially gypsum) which occur, not only in saline solutions, but also in many organic liquids. Investigations have shown the prime necessity of preventing the formation of fresh crystals in the heater, or directly in the heating surface of same, and that, in addition, special measures must be adopted to prevent the deposition and adhesion of any floating crystals already present.

The formation of fresh crystal nuclei has its origin in the super-saturation of the solution, whereby according to the laws of crystallization it is necessary for the metastable zone of super-saturation to have already been exceeded. A saturated solution of a substance the solubility of which decreases with increasing temperature, is super-saturated by heating. The upper limit of the metastable super-saturation zone is thereby exceeded at a determined temperature. The difference between this temperature and the temperature of the saturated solution with the same content of dissolved substance, depends upon the nature of this dissolved substance and amounts to about 1 to 3° centigrade. The discovery of this temperature interval is particularly important in the case of substances whose solubility diminishes on heating, as is the case, for example, with gypsum, when the temperature of the solution rises above about 38° C. A saturated solution may also become super-saturated by concentration. In consequence, in order to avoid deposition of crystals in the heater, it is necessary to prevent in the heater any even local super-saturation above the metastable zone. This means to prevent in the heater first, all concentration or evaporation, second, all local concentration, e. g., formation of steam bubbles

which instantly condense again, third, all super-heating, and fourth, all local superheating near the heating surface.

To obtain these results it is necessary to combine the following four precautions:

(1) To employ a sufficiently high liquid pressure in the heater to keep the boiling point above the heating temperature throughout.

(2) To control the quantity of circulating liquor so as to keep the increase of temperature in the heater in definite limits and to prevent the super-saturation developing in the heater from exceeding the upper limit of the metastable zone.

(3) To keep the temperature drop between the heating medium and the liquid as small as possible, in order to obviate the dangerous influence of the higher wall temperature.

(4) To arrange for the liquid to flow at a high velocity, so that the turbulent flow may effect a thorough intermingling of particles of liquid which may be of different temperatures.

In addition to the foregoing measures, however, it is desirable that certain other points should be observed in order to prevent the deposition and adhesion on the heating surface, of crystals already present in the liquid and circulating through the heater. It is known that the subsidence of coarse floating substances can be prevented by increasing the velocity of flow, and also by employing vertically disposed heating surfaces. In the case of very small crystals, however, the adhesive force may preponderate, so that such crystals adhere to the walls, in spite of the employment of the customary velocities, and especially on the microscopically small irregularities in the wall material, the structure of which exhibits more or less considerable depressions and prominences. Experience has shown that this phenomenon is more particularly seen in the case of gypsum crystals. In order to counteract it, the rapid growth of the crystals must be facilitated, which is effected by relieving the supersaturation of the liquid on the existing crystal nuclei, either completely or at least partially, before the circulating crystals re-enter the heater.

The essence of the present invention consists in combining, for common action, all the aforesaid factors which have a retarding influence on the formation of incrustations. Although some of said measures are already known and have been variously employed, they are not, in themselves, capable of preventing incrustations in the heater, in the long run. Even the employment of two of the different means specified, such as a

high liquid pressure in combination with a high velocity, is altogether inadequate. It has been shown, and this is confirmed by practical experience, that, in order to accomplish the object in view, none of the aforesaid measures must be omitted.

In this connection, reference may be made to the United States Patent No. 1,006,823, which, on superficial examination, seems to display a certain similarity to the process of the present invention.

A fundamental difference, however, exists in that, in carrying out the process of the said United States specification, the formation of fresh crystals cannot be prevented, but, on the contrary, means are adopted for separating the crystals freshly formed in the heater, in a special sludge collector between the heater and the throttle device, in order thereby to obtain a purer salt as end product. Only the first and the fourth of the precautions mentioned above are employed.

In contrast thereto the present invention by also employing the second and the third of the precautions mentioned insures that no formation of crystals takes place in the heater. Incrustation of heating surfaces can not as a matter of fact be effectively prevented in any way if any new crystal nuclei are formed in the heater.

On the other hand, processes are known in which both the metastable saturation is not exceeded, and the growth of the crystals proceeds outside the heater, but in these cases the characteristic of raising the boiling point above the temperature of the heating medium is lacking, as is also the relief of the supersaturation after steam has been given off from the liquid. As a matter of fact, it has not been found possible to prevent incrustations of gypsum and the like in apparatus of this kind, because local superheating and development of steam bubbles directly at the heating surfaces have not been prevented, and velocities of flow are too low.

The following points may be mentioned with regard to the employment of high velocities of flow as a means for preventing the formation of incrustations:—

The velocity is intended to act in a dual capacity, on the one hand, to prevent the deposition of solid constituents on the heating surface, and further to assure thorough intermingling of the liquid, in order that no local rise in temperature, beyond the permissible limit of the metastable zone, can occur. For this purpose, particularly high velocities must be employed, and it has been ascertained that the velocity must, preferably, be at least 1 meter per second, if the desired effect is to be produced. Such high velocities, however, do not, in themselves, ensure the necessary slight heating within the metastable zone, their sole purpose being to render the distribution of temperature more homogeneous in the current of liquid. The slight heating, in turn, necessitates the simultaneous employment of sufficiently large volumes of circulating liquid, and also low heating temperatures, or slight temperature drop at the heating surface. Suitable selection of the dimensions of the heating pipes, and of the working conditions of the circulation pump, will enable the foregoing conditions to be fully met in constructing the apparatus.

The following example serves to explain the conditions once more, on a numerical basis:—

Sulphite waste liquor, neutralized with lime, was concentrated in a circulation evaporator op-

erating under pressure. The solution was in a state of complete saturation with gypsum. The heater was heated by steam at a temperature of 120° C. The pressure in the heating system was 1.3 atmospheres on the liquid side, and therefore no steam could be formed in any part of the heater. The circulation of the liquid was so calculated that, in a single passage through the heater, the rise in temperature amounted only to about 0.8-1° C. At the same time the rate of flow of the liquor in the heater could be maintained at between 1 and 2 meters per second. On entering the evaporator, the heated liquor was allowed to expand to atmospheric pressure, thus allowing the liberation of an amount of steam corresponding to the volume in circulation and the preceding heating, while the temperature of the liquor itself fell from about 101° to 100° C. During the further course of the liquid through the evaporator, the supersaturation resulting from the heating in the heater and also from the liberation of steam in the evaporator, was relieved on the crystal nuclei in the latter, in circulation with the liquor there, the crystals themselves remaining, for the most part, in suspension. In this condition, the liquor was drawn out of the evaporator by suction, and again passed, under corresponding pressure, through the heater, where the supersaturation temperature was again brought by heating up to about 101° C. By this means, the renewed formation of crystals in the heater, or adhesion of the suspended crystals on to the heating surface was prevented, which, as experience has shown, cannot be done in other apparatus.

Now, in carrying out this process, a maximum degree of supersaturation, during the circulation of the liquid, occurs at a certain point in the apparatus. This point of maximum supersaturation can occupy an entirely different position within the circulation, according to the special physical properties possessed by the liquid, and it is important that the saturator, in which the liquid is restored from the supersaturated condition to that of saturation, should be located at the point in question. In some cases a temporary displacement of the point of maximum supersaturation in the circulation of the liquid can be effected through the working conditions selected, so that it seems advantageous to arrange, for example, two saturators at different points, these being either separate from the evaporator, or else structurally connected therewith. In this manner a practically sufficient protection against the formation of any incrustation on the heating surface can also be obtained.

Moreover, in carrying out the process according to the present invention, it is particularly important to take into consideration the fact that the disengagement of steam, subsequent to the expansion in the evaporator, takes place under substantially different conditions from those to which one has been accustomed in the evaporators hitherto in use. These special operative conditions are due, on the one hand to the large volume in circulation and slight difference in the temperature of the liquid before and after the disengagement of the steam, and on the other hand to the high pressure of the liquid prior to the expansion to the pressure of the evaporator. The pressure considered necessary in the heater may be produced by employing columns of liquid of suitable height, but more simply by throttling the circulation of the liquid. Various appliances are known by means of which the complete ex-

pansion of the liquid may be effected. However, in the case of rather large pressure drops the formation of correspondingly large amounts of steam causes certain difficulties in the operation 5 of such apparatus.

The vaporizer is to be operated somewhat like a jet condenser. It requires a good distribution of the injected liquid, or the creation of the largest possible superficial area of the liquid, in order that the liberation of the steam may proceed as extensively as possible, the more so when the temperature drop is very slight. On the other hand, the cross sectional area of throttle apertures depends upon the pressure gradient and must be 15 kept very small when the differences in pressure are great, with the result that the total superficial area of the escaping jets of liquid may not be large enough to enable a rapid and complete disengagement of heat in the form of steam. When 20 the jet of liquid entering the vaporizer has not a sufficiently large surface, the resulting steam tears the jet apart and there are spray losses, while a part of the liquid may re-enter the circuit before the whole amount of steam is given off.

25 The pressure drop of the liquid entering into the vaporizer can be considerably reduced by inserting two throttling stages between heater and vaporizer. In the first stage the liquid leaving the heater may expand to a pressure very little 30 above its boiling point. The pressure drop of the second stage must only be great enough to prevent premature evaporation. In consequence cross sectional areas of the second throttling stage can be large, the superficial area of the jets 35 can be large too, and the steam can be developed without violence. The difference in comparison with the single throttling is particularly large because, owing to the exceedingly slight elevation of the temperature of the liquid in the heater, only 40 a very small pressure is needed to prevent the formation of steam prior to the final expansion, whereas, the liquid pressure in the heater must be substantially higher owing to the higher temperature of the heating medium.

45 The desired subdivision of the expanded jet of liquid can be effected by suitable designed nozzles of small diameter, by longitudinal, transverse or circularly disposed slots, or also by sprinklers, sieves or perforated sheet metal of any kind. The 50 essential point is that, on issuing into the evaporator, the expanded liquid shall be able to display the largest possible surface for the disengagement of steam, and that the discharge velocity shall remain at a minimum.

55 The performance of the process also requires, as a preliminary condition, that the slight degree of heating of the liquid, as prescribed by the invention and in which the zone of metastable saturation must not be exceeded, necessitates, as 60 a matter of course, the employment of larger volumes than usual in circulation, a condition which, in conjunction with the requisite generation of pressure in the heater, entails a not inconsiderable expenditure of energy for the circulation pump.

65 The economy of the process can be still further improved by employing, instead of electricity, for driving the pump, a steam turbine, the exhaust steam from which is passed into the heater. In a plant comprising a plurality of units, it will be advisable to employ the exhaust steam from each stage of the turbine for heating the first stage of the evaporators, in order 70 to obtain a multiple utilization of the exhaust steam in accordance with the number of units.

75 In order more clearly to understand the nature

of the invention, reference is made to the accompanying drawing, which illustrates diagrammatically and by way of example, a typical embodiment of apparatus suitable for carrying out the process of the invention. In said typical embodiment, 1 is the evaporator and 2 the heater, both being adapted to be operated under any convenience pressure, or also under a vacuum. The evaporator 1 is connected to the heater 2 by the pipes 3 and 5 on the one hand, and the pipe 11 on the other. The circulation pump 6, driven by the steam turbine 7, is connected up in the pipe 5. The working steam for the turbine 7 is admitted at 8. The exhaust pipe 9 is connected to the heater 2. The additional heating steam required is supplied through pipe 10, and may also, if desired, be wholly or partially replaced by the exhaust turbine steam from the succeeding evaporator stages in a multiple-unit plant. Compressed evaporator steam may also serve as heating steam. The connecting pipe 11 comprises a throttle device 12, by means of which the liquid pressure is so far reduced, by comparison with that in the heater 2, that the boiling point of the liquid is only slightly higher than 100 the liquid temperature prevailing at this point. The complete expansion to the absolute pressure in the evaporator 1 then takes place at 13. The steam thus disengaged from the liquid passes away through the branch 14 and may, for example, be led to a condenser, a compressor or a second evaporator stage. Each of the throttles 12 and 13 may, of course, be controlled in known manner, and either independently or conjointly. According to the physical properties of the 105 liquid, the saturator 4 may be located at one or more points in the liquid circulation, for example between the evaporator 1 and the circulation pump 5, or between the two throttling stages 12 and 13. The saturator 4 may also be connected 110 with the evaporator 1 as a structural unit, or also arranged to be disconnected. The pipe 15 serves for evacuating the saturator 4.

When the apparatus is in operation, the liquid therefore flows, under the pressure effected by 120 the pump 6, for example through the heater 2 and pipe 11, then through the first throttling stage 13 and into the evaporator 1, from which, after the disengagement of steam, it returns through the saturator 4 to the circulation pump 125 6. In the case of other liquids, or other working conditions, the following serial order, for example, may be suitable; from the pump 6, through the heater 2, riser pipe 11, first throttling stage 12, saturator 4, second throttling stage 13, evaporator 1 and direct to the pump 6. After being sufficiently concentrated, the liquid is drawn 130 off from the evaporator at 16.

The process may, of course, be carried on under pressure or under a vacuum, and also in combination with vapor compressors. Evaporators of this kind may also be run with a plurality of units, each evaporator having its own circulation pump, throttle devices, saturator, and so forth, as shown in the drawing. Bearing also 135 in mind that the high velocity required, according to the invention, in the heater, is accompanied by a substantial increase in the transmission of heat, it will at once be evident that the process according to the present invention allows 140 of the economical concentration of even such liquids as were hitherto a source of difficulties owing to incrustation.

I claim:

1. A process of concentrating liquids contain- 150

ing calcium sulfate or like substances of negative temperature coefficient of solubility by circulating the liquids through a heating stage and an evaporating stage which comprises causing the liquids to flow through a heater at a pressure such that the boiling point of the liquid is higher than the temperature of the heating medium, controlling the quantity of circulating liquid in such manner that the supersaturation caused by the increase of temperature in the heater does not exceed the upper limit of the metastable zone, relieving the supersaturation of the incrustants in the liquid after it is withdrawn from the heater and before it is returned thereto and releasing the pressure on said liquid upon passing into the evaporator.

2. A process of concentrating liquids containing calcium sulfate or like substances of negative temperature coefficient of solubility by circulating the liquids through a heating stage and an evaporating stage which comprises passing the liquid in heat exchange relation with a heating medium at a velocity of at least one meter per second while maintaining the liquid at a pressure such that the boiling point of the liquid is higher than the temperature of the heating medium, controlling the heating of the liquid in such manner that the super-saturation caused by the increase of temperature during the heating stage does not exceed the upper limit of the meta-stable zone, relieving the super-saturation of the incrustants in the liquid after it is withdrawn from the heating stage and before it is returned thereto and releasing the pressure on said liquid during passage through the evaporating stage.

3. A process of concentrating liquids containing calcium sulfate or like substances of negative temperature coefficient of solubility by circulating the liquids through a heating stage and an evaporating stage which comprises passing the liquid in heat exchange relation with a

heating medium at a velocity of at least one meter per second while maintaining the liquid at a pressure such that the boiling point of the liquid is higher than the temperature of the heating medium, controlling the heating of the liquid in such manner that the super-saturation caused by the increase of temperature during the heating stage does not exceed the upper limit of the metastable zone, keeping the difference in temperature between the liquid flowing through the heating stage and the heating medium below 20° C., relieving the super-saturation of the incrustants in the liquid after it is withdrawn from the heating stage and before it is returned thereto and releasing the pressure on said liquid during passage through the evaporating stage.

4. A process of concentrating liquids containing calcium sulfate or like substances of negative temperature coefficient of solubility by circulating the liquids through a heating stage and an evaporating stage which comprises passing the liquid in heat exchange relation with a heating medium at a velocity of at least one meter per second while maintaining the liquid at a pressure such that the boiling point of the liquid is higher than the temperature of the heating medium, controlling the heating of the liquid in such manner that the super-saturation caused by the increase of temperature during the heating stage does not exceed the upper limit of the meta-stable zone, keeping the difference in temperature between the liquid flowing through the heating stage and the heating medium below 20° C., relieving the super-saturation of the incrustants in the liquid after it is withdrawn from the heating stage and before it is returned thereto and releasing the pressure on said liquid during passage through the evaporating stage.
